US00D585375S

(12) **United States Design Patent**
Andre et al.

(10) **Patent No.:** US D585,375 S
(45) **Date of Patent:** ** Jan. 27, 2009

(54) **POWER CONNECTOR**

(75) Inventors: **Bartley K. Andre**, Menlo Park, CA (US); **Daniel J. Coster**, San Francisco, CA (US); **Daniele De Iuliis**, San Francisco, CA (US); **Richard P. Howarth**, San Francisco, CA (US); **Jonathan P. Ive**, San Francisco, CA (US); **Duncan Robert Kerr**, San Francisco, CA (US); **Shin Nishibori**, San Francisco, CA (US); **Matthew Dean Rohrbach**, San Francisco, CA (US); **Peter Russell-Clarke**, San Francisco, CA (US); **Douglas B. Satzger**, Menlo Park, CA (US); **Calvin Q. Seid**, Palo Alto, CA (US); **Vincent Keane Seid**, legal representative, Los Gatos, CA (US); **Christopher J. Stringer**, Portola Valley, CA (US); **Eugene Antony Whang**, San Francisco, CA (US); **Rico Zorkendorfer**, San Francisco, CA (US)

(73) Assignee: **Apple Inc.**, Cupertino, CA (US)

(**) Term: **14 Years**

(21) Appl. No.: **29/281,458**

(22) Filed: **Jun. 22, 2007**

(51) **LOC (9) Cl.** 13-03

(52) **U.S. Cl.** D13/133; D13/144

(58) **Field of Classification Search** D13/133, D13/144, 154, 156, 184, 199; 439/675, 699, 439/750

(57) **CLAIM**

The ornamental design for a power connector, substantially as shown and described.

DESCRIPTION

FIG. 1 is a front perspective view of a power connector showing our new design;

FIG. 2 is a rear perspective view thereof;

FIG. 3 is a front view thereof;

FIG. 4 is a rear view thereof;

FIG. 5 is a side view thereof;

FIG. 6 is another side view thereof;

FIG. 7 is a rear perspective view of an alternate embodiment of our new design; and,

FIG. 8 is a rear view thereof.

The broken lines in the Figures are for illustrative purposes only and form no part of the claimed design.
